UNITED STATES PATENT OFFICE.

ERNEST WINNE, OF NEW YORK, N. Y.

FOUNTAIN-PEN.

1,195,125.

Specification of Letters Patent. Patented Aug. 15, 1916.

Application filed May 29, 1915. Serial No. 31,146.

To all whom it may concern:

Be it known that I, ERNEST WINNE, a citizen of the United States, and a resident of New York city, borough of Manhattan, in the county of New York and State of New York, have invented certain new and useful Improvements in Fountain-Pens, of which the following is a specification.

This invention relates to certain new and useful improvements in fountain pens, and particularly to that class of fountain pens which are provided with an automatic filling device composed of a compressible reservoir and means for excluding the air from the reservoir so as to permit the ink to flow in.

The object of my invention is to provide a new and improved pen of this kind which is simple in construction, can be manipulated with the least expenditure of time and effort, and which does not require the detaching or preliminary shifting of any parts whatever, nor the use of any other instrument than the fingers directly applied; which does not have any parts projecting from the side of the barrel to interfere with the convenient holding of the pen when in use, or detract from its graceful appearance; and in the operation of which there is no tendency to force the pen toward the bottom of the ink well; and which improvement is strong and durable, and operates rapidly.

In the accompanying drawings in which like letters of reference indicate like parts in all the figures:—Figure 1 is a longitudinal section of my improved self-filling fountain pen. Fig. 2 is an enlarged detail longitudinal sectional view of the upper end of the barrel, the plunger, and the means for moving the same. Fig. 3 is a transverse section on the line *a—a* of Fig. 2. Fig. 4 is a transverse section on the line *b—b* of Fig. 2. Fig. 5 is a transverse section on the line *c—c* of Fig. 2. Fig. 6 is a perspective view of the sleeve cam, parts being broken away.

The pen barrel 1 contains a compressible ink reservoir 2 which preferably consists of a longitudinal bag of rubber. This bag can be compressed so as to force out the air by means of a strip 3, which is secured to a spring strip 4 placed in the barrel alongside of the reservoir, both of which extend longitudinally of the reservoir. This spring strip 4 or flexible strip at its lower end rests against the front plug,—the part containing

the nib and feed,—and at the upper end of the barrel ends in a plug or plunger 5 which is longitudinally movable in an aperture through a cylindrical cross piece or partition 7, near the upper end of the barrel, in which aperture said plunger is guided to move longitudinally. When the compressible reservoir is filled and distended by the ink in the same, the strip 4 is straightened out and rests against the wall of the barrel. When the plunger 5 is moved inward longitudinally, the spring strip 4 is bent at its center and presses the strip 3 against the ink reservoir, thereby flattening or compressing the reservoir and forcing out the ink or air so that when the pressure on the plunger 5 is removed the distending reservoir can flatten out the spring strip 4. What I have described so far I do not claim as my invention.

In my invention the plunger 5 is guided to move lengthwise of the barrel, and also is prevented from turning, by means of a pin or other projection 8 extending from each of two opposite sides of the same, beyond the partition 7, through two opposite longitudinal slots 9 formed in the neck 10 of the barrel beyond the partition 7. A sleeve 11 fitting on the cylindrical partition 7 and neck 10, and preferably having its outer surface provided with longitudinal ruffles,—or roughened in any other way that will facilitate its being firmly grasped with the fingers,—fits snugly but capable of easy turning on the partition and neck; and on the inside of this sleeve 11, bearing directly on the neck, a metal sleeve or bushing 12 is firmly inserted, which has its inner edge shaped as a cam edge, which cam edge bears upon the ends of the projections 8, which projections extend to the inner diameter of the sleeve 11 at that part not provided with cam sleeve 12. The cam sleeve is thus mounted to rotate on the neck by manipulation of the sleeve 11 of which it is a fixed part. To prevent the sleeve 11 and its cam sleeve bushing 12 from moving longitudinally a sleeve 13 is slipped upon the neck 10 and rests against the outer ends of the sleeves 11 and 12, thus holding the opposite end of the sleeve 11 against the shoulder at the end of the main portion of the barrel. The sleeve 13 has two diametrically opposite longitudinal ridges 14 which pass into the grooves 9 and thus prevent the sleeve 13 from revolving. The outer edge of the

sleeve 13 is flush with the extreme outer edge of the pen barrel, which is the outer end of the slotted neck. To prevent the sleeve 13 from moving longitudinally an end plate 15 is secured on the end of the barrel to overlap the outer edges of the sleeve 13, and this end piece is preferably held in place by providing it with a threaded stem 16 which can be screwed into the outer end of the neck 10, which is internally screw threaded for the purpose of receiving this screw.

The sleeve 11 can be turned on the neck in either direction, but cannot move longitudinally, as it is confined by the sleeve 13, which cannot turn on account of its internal ribs or splines 14, and cannot move lengthwise on account of the retaining plate or head 15 of the screw at the end of the barrel. By turning the sleeve 11 axially the cam edges 19 on the inner end of the inserted metal sleeve 12, which is secured on the sleeve 11, act on the projections 8 and press the plunger 6 lengthwise of the barrel in the direction of the pen-holding end of the same, thereby upsetting the spring strip 4, whereby the strip 3 which is attached to the middle of the spring 4 exerts a uniform pressure on the side of the compressible reservoir 2, thus expelling the ink and air therefrom, but as soon as the point of the cam edge 19 has passed the projections 8 the inrushing ink distends the reservoir 2, flattens out the spring strip 4, and pushes the plunger 5 outward again. Hence it is only necessary to give the sleeve 11 an axial movement in either direction of one-quarter of a revolution, it being understood that there are four cam projections 19 on the sleeve 12. In so turning the cam sleeve, when the points of the cam pass the projections 8 the latter return with a snapping movement into the bottom of the notches between the cam points, and this single pressure and release movement of the cam sleeve is sufficient to expel the air from the reservoir and to permit the reservoir to be filled with ink after it has thus been compressed and permitted to expand. The cam sleeve 12 can be turned in either direction as the cam edges 19 incline at an equal angle in both directions. Therefore, to fill the pen, all that is necessary is to dip the pen point into the ink and to grasp the barrel firmly between the pen point and the sleeve 11 and then turn said sleeve in either direction a quarter revolution, or until the mechanism snaps back into its normal position; or, with the usual pen-covering cap resting firmly on the sleeve 13 so as to turn with the same, the sleeve 11 is grasped firmly between two fingers, the pen point is inserted in the ink, and the entire barrel is turned axially by turning the cap, it being understood that the sleeve 11 remains firmly grasped between the fingers.

Having described my invention, what I

claim as new and desire to secure by Letters Patent is:—

1. In an automatic filling fountain pen, the combination with a barrel and a compressible reservoir in the same, of means for compressing said reservoir, comprising a plunger, guided to move lengthwise, means for holding the plunger against rotary movement, a rotary sleeve provided with internal cams to act on said plunger and means secured on the barrel adjacent to the cam sleeve, to prevent longitudinal movement of the latter, substantially as set forth.

2. In an automatically filling fountain pen, the combination with a barrel and compressible reservoir in the same, of means for compressing the reservoir comprising a plunger guided to move lengthwise, a sleeve provided with internal cams to act on the plunger, a sleeve abutting the cam sleeve to prevent longitudinal movement of the latter and means for preventing said last mentioned sleeve from turning and means for preventing said sleeve from moving longitudinally, substantially as set forth. 90

3. In an automatically filling fountain pen, the combination with a barrel and compressible reservoir in the same, of means for compressing the reservoir comprising a plunger guided to move lengthwise, a sleeve provided with internal cams to act on the plunger, a sleeve resting against the outer end of the cam sleeve to prevent the latter from moving longitudinally, means for preventing said sleeve from turning and an end piece to prevent said sleeve from moving longitudinally, which end piece has a screw stem, screwed into the outer end of the barrel, substantially as set forth. 10

4. In an automatically filling fountain pen, the combination with a barrel and a compressible ink reservoir in the same, of means for compressing the reservoir comprising a plunger guided to move longitudinally, two opposite projections laterally extending from said plunger, the barrel having longitudinal grooves in which said projections can slide, a cam sleeve provided with internal cams to bear against said projections, and means for preventing the cam sleeve from moving lengthwise, substantially as set forth. 11

5. In an automatically filling fountain pen, the combination with a barrel and a compressible ink reservoir in the same, of means for compressing the reservoir comprising a plunger guided to move longitudinally, two opposite lateral projections on said plunger, the barrel having longitudinal grooves in which said projections can slide, a sleeve mounted on the barrel at the location of said lateral projections, a metal cam sleeve inserted into said sleeve and secured therein against longitudinal movement, the cam edges of the cam sleeve bear- 12 13

ing against the said projections, and means for preventing the sleeve in which the cam is provided from moving lengthwise, substantially as set forth.

5 6. In an automatically filling fountain pen, the combination with a barrel and a compressible ink reservoir in the same, of means for compressing the reservoir comprising a plunger guided to move lengthwise 10 and having two opposite laterally extending projections, the barrel terminating in a neck which is slotted lengthwise, through which slots the ends of the projections on the plunger extend, a cam sleeve on said neck provided with internal cams bearing on said 15 projections, a sleeve resting against the outer end of the cam sleeve and having internal projections which enter the slots in the neck, and means for preventing said 20 last named sleeve from moving lengthwise, substantially as set forth.

7. In an automatically filling fountain pen, the combination with a barrel and a compressible ink reservoir in the same, of 25 means for compressing the reservoir comprising a plunger guided to move lengthwise and having two opposite laterally extending projections, the barrel terminating in a neck which is slotted lengthwise, through which 30 slots the ends of the lateral projections on the plunger extend, a cam sleeve on said neck provided with internal cams bearing on said projections, a sleeve resting against the outer end of the cam sleeve and having internal 35 projections which enter the slots in the neck, an end plate resting against the

last mentioned sleeve, a threaded stem projecting from said plate, which threaded stem is screwed into the end of the barrel, substantially as set forth.

40

8. In an automatic filling fountain pen, the combination with a barrel, a compressible reservoir therein, of means for compressing the reservoir, comprising a plunger guided to move lengthwise, means for preventing rotary movement of the plunger, a loosely mounted sleeve which can be rotated in opposite directions, cam edges in said sleeve to act on said plunger to move it lengthwise in the same direction when the 50 sleeve is rotated in either direction and means to prevent longitudinal movement of the cam sleeve, substantially as set forth.

9. In an automatic filling fountain pen, the combination with a barrel, of a compressible reservoir therein, means for compressing the reservoir comprising a plunger guided to move lengthwise and a sleeve on the barrel which is mounted to rotate in opposite directions, means for preventing 55 rotary movement of the plunger, the plunger being operable by the sleeve with the same effect when the same is turned in either direction, substantially as set forth.

Signed at New York city, borough of 60 Manhattan, in the county of New York and State of New York this 11th day of March, 65 A. D. 1915.

ERNEST WINNE.
